PROCESS FOR PRODUCING DECORATED SURFACES

Karl Eichstädt, Berlin, Germany, assignor to
Oxford Varnish Corporation, Detroit, Mich., a
corporation of Michigan

Application November 16, 1933, Serial No. 698,328
In Germany November 26, 1932

2 Claims. (Cl. 41—35)

This invention relates to a process for producing a decorated surface, and is especially concerned with the production of artificial marble, tile and the like.

- 5 5. It is well known that artificial marble or other stone may be manufactured by mixing substances which will readily harden, pouring or otherwise placing such mixture into a form, and removing the form after the mixture has hardened or set.
- 10 10. One of the well known mixtures is cement. After the form is removed, the surface of the hardened object is decorated to simulate a natural stone. It has been found however, that it is difficult and costly to decorate the surfaces of such imitation
- 15 15. or artificial stone and even when such stone is decorated such an artificial stone surface finish is not permanent.

The general object of the present invention is to provide a method of decorating artificial stone surfaces to simulate natural stones.

A further object is to provide a method of manufacturing artificial stone or the like, which method will provide the artificial stone with a surface decorated to simulate a natural stone or 25 similar object.

Other objects of my invention will be set forth in the following description, reference being had to the accompanying drawing, and the essential novel features of my improved method will be 30 characterized in the claims.

I have found that the difficulties mentioned may be partially overcome by eliminating from the ingredients of the colors, all oils or greases, and I preferably use colors having a spirit or 35 nitrocellulose vehicle. In applying such colors to the artificial stone, which is naturally porous, the color will sink into the pores and after the evaporation of the vehicle, the surface can be covered with a topcoat depending upon the resistance required in the finished product, such as 40 the resistance to water or oil. The process is especially adapted for the production of patterns with the intaglio process, since the intaglio process is well adapted for handling colors of this type.

45. By using colors which are free from greases and oils, and which preferably have a spirit or nitrocellulose vehicle as above set out, much of the difficulty of decorating artificial stone is eliminated. However, even then the process 50 when put into actual practice has been of limited use due to the lack of practical colors.

To enlarge the range of colors that may be used to practical advantage, I find it advantageous to depart from the usual process of applying the 55 colors to the surfaces to be decorated and pro-

vide a method for applying the colors to the artificial stone in an indirect manner. This therefore is one of the objects of my invention.

Briefly my improved method of applying designs in color to artificial stone comprises printing or otherwise applying color to a highly polished or other surface from which the color is readily removed after the drying of the vehicle used in the color, then by using raw and/or partially prepared materials, I form the slab itself 10 over said colored surface, and after the formation of the slab is complete, I strip the slab with the color adhering to it from the surface on which the color was originally laid. The surface may then be treated in the usual manner with a top or 15 wearing coat of varnish or lacquer.

Referring now to the drawing, Fig. 1, wherein I illustrate the various steps of my invention, is a section through a polished plate; Fig. 2 illustrates diagrammatically an offset printing or decorative 20 press, placing the pattern in color on the polished slab or sheet; Figs. 2 to 6 inclusive are sections in planes similar to Fig. 1, but illustrating the article after different steps of my improved method have been performed; Figs. 7 and 8 are similar to Figs. 25 3 and 6, but are representative of a modification of the method shown in Figs. 1 to 6, inclusive.

Referring again to the drawing, 10 represents a slab or plate from which color, when dried thereon, may readily be stripped. I prefer to use 30 for this purpose a highly polished plate, as, for instance, glass. I then apply the design in color to this polished surface 11 of the plate 10.

In Fig. 2, I diagrammatically show a printing or decorating press which may be used to print 35 the design on the polished plate. As shown, the press includes a master plate or roll 12 having a variegated indented surface, to which pigment is supplied by a fountain roll 14. The lower region of the fountain roll rotates in a fountain 15, 40 which is supplied with color in any well known manner. The surplus ink or color is removed or scraped from the surface of the master roll by a scraper or doctor blade 16. The scraped surface of the master roll then contacts with a rubber or 45 gum offset roll 17 to effect a transfer of the color from the interstices to the surface to be decorated. The offset roll in turn contacts with the polished surface 11 of the slab 10 to effect the transfer of the color 19 from the offset roll to the 50 plate. The plate 10 is supported in any suitable manner such, as for instance, on a compression roll 20. A suitable scraper 21 removes any color remaining on the offset roll after the transfer to the polished surface 11 has been effected. This 55

type of press has been chosen for ease of illustration. However, any type of press may be used, or the color may be applied directly to the polished surface 11 by hand.

5 After the design color 19 on the plate 10 has dried, I pour or otherwise place on the decorated plate 10 an artificial stone composition. Such compositions are well known at the present time and need not be herein described in detail. Many 10 types of composition contain materials such as cement, lime or plaster of Paris, and are poured on the plate as a plastic mass and upon drying form a hard substance simulating stone. Other materials, such as gypsum, pulpwood and the like 15 are compressed to solidify them.

In Fig. 2, I illustrate the plate 10 after the design or color 19 has been applied. The color on the plate 10 is then dried and the plate placed in a suitable form 25, shown in Fig. 3. The form 20 is then filled with the composition which will form the artificial stone. After the composition has dried or otherwise become set, the form is removed and the solidified mass is stripped from the plate 10, the color or design 19 adhering to 25 the mass. When the plate 10 comprises a highly polished plate, such as polished glass, the surface of the artificial stone will have a high degree of polish, depending upon the degree of polish of the plate 10 and the fineness of the material used in 30 the composition. When the plate 10 is polished glass and when the composition includes cement, the surface of the finished slab will impart to it a high glass such as is desired on artificial marble and other types. The surface may then be 35 treated with the usual top coat to preserve its finish.

The colors used are preferably such that they 40 will not be affected by the materials forming the composition stone, and will have greater adhesiveness to stone than to the supporting surface. Likewise, the vehicle used in the colors must be 45 such that it will not be affected in any way by the material forming the artificial stone. In instances where the composition contains cement or lime, it is preferable that the vehicle contains no oils, 50 fats, resins or gums, but that it be composed of casein glue, silicate of soda, and the like.

In Figs. 7 and 8, I illustrate a modified form of 55 my invention in which the plate 10a is a highly polished metallic plate and is first decorated by any well known process with color which is indicated at 48, next a ground or base coat 49 is applied to provide a background for the colors and to prevent the composition forming the artificial stone from appearing through the design. These 55 color coats are dried and the plate 10a placed in a press 42. The material to comprise the artificial stone is next placed on the colored surface

of the slab and pressure is applied to compress the material to form the slab 45. After the material has been compressed and has set or hardened, it is removed from the plate 10a, the colors 5 adhering to the material due to the presence of adhesives or the like in the composition, such as, for instance, the presence of glue or similar materials in a composition containing pulpwood or other fibrous materials. In some instances asphaltic cements may be used as a binder for the 10 materials and as an adhesive.

From the foregoing description, it is readily seen that I have provided a simple and inexpensive method of decorating the surfaces of artificial stone and similar materials. It is also seen that 15 the color may be applied manually or with any well known printing or similar process.

I claim:

1. The method of forming an artificial stone in simulation of a natural stone, comprising reproducing the natural stone by a photogravure method, transferring such reproduction in color to portions of a polished surface, applying a layer 20 of pigment over the entire surface and over said color, applying a plastic material to said coated 25 surface, solidifying said material by the application of pressure thereto, there being a greater degree of adhesion between said material and said pigment and between said pigment layer and said reproduction than there is between said color 30 and/or said reproduction and said surface, and subsequently removing said solidified material and coatings as a unit from said surface.

2. The method of producing artificial materials having artistic designs simulating the natural 35 appearance of the surface to be imitated, which comprises making a photographic reproduction of the article to be simulated, producing a printing member from the reproduction, applying pigment to such printing member, removing the excess pigment therefrom, transferring the pigment 40 from the printing member to a highly polished surface, such pigment corresponding in color to one of the colors of the natural article being simulated and being in the form of an open 45 design, which, when applied, leaves uncovered portions of said polished surface, subsequently applying to said layer and to said uncovered portions of the polished surface a layer of pigment 50 corresponding in color to the dominating color of the natural surface being imitated, applying a layer of plastic cementitious material on said pigment layers, solidifying said plastic material 55 to form a hardened slab by the application of pressure thereto, and subsequently removing all of said layers as a unit from said polished surface.

KARL EICHSTÄDT.
